APPARATUS AND METHOD FOR SEALING
WAXED WRAPPERSRalph A. Hayward, Parchment, Mich., assignor
to Kalamazoo Vegetable Parchment Company,
Parchment, Mich.

Application December 31, 1935, Serial No. 56,943

14 Claims. (Cl. 93—2)

In the wrapping and sealing of articles in waxed wrappers, it is a very general practice to wrap the article, for example bread, in a waxed wrapper, overlapping the sealing flaps or folds, 5 and to subject such overlapped sealing flaps or folds to the heat and pressure of a sealing plate designed to fuse the wax and press the overlapping folds together. Speed is desirable and owing to the momentary contact with the sealing plate, it frequently happens that the sealing is 10 ineffective particularly where the wrappers are not heavily waxed.

The main objects of this invention are:

First, to provide an improved method of sealing 15 waxed wrappers, whereby a more effective sealing results even where there is considerable variation in the sealing pressure and temperature, such for example as is occasioned by irregularities in the article wrapped.

Second, to provide an improved method of sealing waxed wrappers which not only secures more effective sealing but permits higher speeds.

Third, to provide an apparatus for performing 25 the method, which is very simple and practical.

Objects relating to details and economies of my invention will appear from the description to follow. The invention is defined and pointed out 30 in the claims.

A structure which is a preferred embodiment 35 of my invention is illustrated in the accompanying drawing, in which:

Fig. 1 is a diagrammatic view illustrating the initial wrapping step, the apparatus being conventionally shown.

Figs. 2, 3, 4 and 5 are perspective views illustrating succeeding steps in the flap forming and folding or closing operations with means for performing such operations.

Fig. 6 is a fragmentary view illustrating means 40 for introducing a limited amount of water between the folded flaps prior to the complete closing thereof.

Fig. 7 is a fragmentary view illustrating means 45 for introducing a limited amount of steam between the folded flaps or into the folds of the flaps prior to the complete closing thereof.

Fig. 8 is a view illustrating the succeeding step, 50 namely, that of applying heat and pressure to the superimposed flaps.

Fig. 9 is a perspective view of the wrapped article.

In the embodiment illustrated, 1 represents 55 an article to be wrapped—in this instance a loaf of bread. 2 represents a wrapping and sealing

conveyor, 3 a bottom folder, and 4 a rear end flap. These parts are conventionally shown.

A wrapper is indicated at 5. This wrapper is positioned across the path of the article to be wrapped as it is delivered to the wrapping mechanism by means of the plunger 6. The carrying of the article between the conveyor way and the bottom folder member 3 drapes the wrapper over the article as shown in Fig. 2. The bottom folder 3 and the rear end flap folder 4 are then reciprocated to fold the bottom flap 61 of the wrapper below the article as shown in Fig. 3 and to form the rear end flap 7 as indicated in Fig. 4. As the article is carried forward onto the conveyor way 2, the front portion of the wrapper is lapped upon 15 the rear bottom portion 61 thereof. As the article is carried forward, it comes into engagement with the front end flap folder 8 which turns in the front end flap 9. This turning in of the front and rear end flaps produces the top end flap 20 10 and bottom end flap 11. The bottom end flap is turned upwardly by means of the stationary folder 12. The top folder 13 is designed to reciprocate to close the top flap 10. However, before the flaps are completely closed, I introduce a 25 limited amount of water between the flaps by means of the nozzle 14 which is connected to a source of supply 15 through a valved dropper mechanism 16, a drop of water being indicated at 17.

The nozzle 14 is directed and positioned so that one or more drops of water will drop between the flaps prior to the complete closing thereof. The closure flaps are then brought into engagement with the sealing pressure plate 18, the temperature of which is such as to convert the water into steam which flows into or enters the spaces between the folds and greatly facilitates the distribution of heat and the fusing of the wax, with the result that a more effective sealing is had 40 even with a minimum amount of wax.

In Fig. 7, I illustrate a modification in which steam is introduced into the folds or flaps through a suitable nozzle 19. In practice, this nozzle would be tripped by the article sealed or some other suitable means in timed relation to the delivery to the sealing plates. The steam acts the same as the steam generated from the drops of water to facilitate distribution of heat to the parts to be sealed and any steam that may be 50 condensed in contacting with the cold wrapper is reconverted when the wrapper is brought into contact with the sealing plate.

It will be understood that the contact of the 55

sealing flaps with the heating means is momentary and frequently the speed of the wrapping is limited by the speed of sealing but even at the same speed it is very desirable to improve the effectiveness of the sealing and this has been accomplished in a very simple manner.

I have illustrated the various steps mainly in conventional form as it will be understood that my improvements may be embodied in or adapted to various forms of wrapping machines now in use. While the method is particularly desirable in wrapping articles in which the wrapper has superimposed end flaps of the character illustrated, it is advantageous to use it wherever there are overlapping waxed parts to be sealed. I have not attempted to illustrate these various adaptations as it is believed that this disclosure will enable those skilled in the art to embody or adapt my improvements as may be desired.

Having thus described my invention, what I claim as new and desire to secure by Letters Patent, is:

1. In a sealing means for waxed wrappers, the combination of sealing flap folding means arranged to form and fold front, rear, bottom and top flaps in the order named, means for introducing a limited amount of water into the flaps before the top flap is closed, and a heating means acting upon the closed flaps whereby the water is converted into steam and facilitates the distribution of heat and the fusing of the wax.

2. In an apparatus of the class described, the combination with means for forming overlapping closure flaps, of means for introducing a limited amount of water between the flaps, and a sealing plate coating with the closure flaps after the water has been introduced therebetween whereby the water is converted to steam during the sealing step.

3. An apparatus for wrapping and sealing articles comprising means for wrapping an article with a waxed wrapper with overlapping sealing flaps, means for introducing water between the folds prior to the complete closing thereof, and a heating and pressing means acting upon the superimposed sealing flaps after the water has been introduced therein.

4. An apparatus for sealing articles comprising means for wrapping the articles with a waxed wrapper with overlapping sealing parts, means for introducing steam between the folds prior to the complete closing thereof, and a heating and pressing means acting upon the superimposed sealing parts after the steam has been introduced therein.

5. An apparatus for wrapping and sealing articles comprising means for wrapping an article with a waxed wrapper with overlapping sealing parts, means for introducing moisture between the overlapping parts, and means acting in sequence for heating and pressing such overlapping sealing parts.

6. The method of sealing waxed wrappers which consists of wrapping the article and partially closing the sealing portion thereof, introducing a limited amount of water into such partially closed sealing portions, and promptly thereafter subjecting the sealing portions to heat and pressure whereby the water is converted to steam which acts to facilitate the distribution of heat and the fusing of the wax.

7. The method of sealing waxed wrappers including the steps of bringing the sealing parts of the wrapper into overlapping relation with a limited amount of water between them, and applying heat and pressure to the zone to be sealed, the temperature of the heating means being such as to convert the water into steam which acts to facilitate the distribution of heat and fusing of the wax.

8. The method of sealing waxed wrappers comprising the steps of forming overlapping closure parts, introducing a limited amount of water between overlapping parts to be sealed, and applying external heat and pressure to the overlapping parts, the heat being sufficient to convert the water into steam.

9. The method of sealing waxed wrappers comprising the steps of forming overlapping closure flaps, introducing a limited amount of water between overlapping flaps to be sealed, and applying external heat and pressure to the overlapping flaps, the heat being sufficient to convert the water into steam.

10. The method of sealing waxed wrappers comprising the steps of forming overlapping closure flaps, introducing steam between the overlapping closure flaps, and applying external heat and pressure to such overlapping flaps.

11. The method of sealing waxed wrappers comprising the steps of forming overlapping closure parts, introducing moisture between the overlapping closure parts, and applying external heat and pressure to the overlapping parts to be sealed.

12. The method of sealing waxed wrappers comprising the steps of forming overlapping closure parts, discharging a jet of steam thereto, and immediately thereafter applying external heat and pressure to the parts to be sealed.

13. The method of sealing waxed wrappers comprising the steps of bringing the sealing parts of the wrapper into overlapping relation, introducing moisture locally adjacent the surfaces to be sealed, and applying heat and pressure to the zone to be sealed.

14. The method of sealing waxed wrappers comprising the steps of bringing the sealing parts of the wrapper into overlapping relation, introducing steam locally adjacent the surfaces to be sealed, and applying heat and pressure to the zone to be sealed.

RALPH A. HAYWARD.
